UNITED STATES PATENT OFFICE.

WILLIAM G. NELSON, OF RACINE, WISCONSIN.

ELECTRIC HEATING AND REGULATING DEVICE FOR INCUBATORS.

1,388,966.

Specification of Letters Patent. Patented Aug. 30, 1921.

Application filed January 15, 1920. Serial No. 351,520.

To all whom it may concern:

Be it known that I, WILLIAM G. NELSON, a citizen of the United States, and resident of Racine, in the county of Racine and State 5 of Wisconsin, have invented new and useful Improvements in Electric Heating and Regulating Devices for Incubators, of which the following is a description, reference being had to the accompanying drawings, which 10 are a part of this specification.

The present invention relates to certain new and useful improvements in incubators and refers more particularly to the heating means therefor.

15 One object of my invention is to provide thermostatically controlled electric heating means operable to automatically open and close the circuit to control the heat within the incubator upon temperature changes 20 therein.

Another object of my invention is to provide an ether filled thermostatic expansion chamber connected with the circuit controlled member whereby changes in the temperature of the incubator will be transmitted to said chamber in the form of a movement to or from the circuit closing position according to the change in temperature.

A further object of this invention is to 30 provide means for adjusting the degree of heat at which the circuit is opened or closed.

A still further object of this invention is to provide a compact heating unit for incubators which may be readily embodied in 35 incubators now in use or in incubators at the time of manufacture.

With the above and other objects in view which will appear as the description proceeds, my invention resides in the novel 40 construction, combination and arrangement of parts substantially as hereinafter described and more particularly defined by the appended claims, it being understood that such changes in the precise embodiment of 45 the herein disclosed invention may be made as come within the scope of the claims.

In the accompanying drawing I have illustrated one complete example of the physical embodiment of my invention constructed 50 according to the best mode I have so far devised for the practical application of the principles thereof, and in which:

Figure 1 is a perspective view of an in-

cubator equipped with my improved form of heating unit, and

55 Fig. 2 is an enlarged view part in section and part in elevation of my complete heating unit.

Referring now more particularly to the accompanying drawing, the numeral 5 designates an incubator of any desired style or construction having disposed therein suitable heating elements 6 having electrical feed wires 7 connected therewith. The feed wires 7 are connected with a suitable source 60 of supply by means of an electric cord 8 adapted to have its end 9 engaged with a main feed line.

65 One of the feed wires 7 is broken and has the ends thereof connected to a detachable plug 10 having two contact points 11 passed outwardly through the adjacent wall 5' of the incubator, the contacts 11 being connected with the ends of the wire 7 having a break therein. As will be readily understood by those skilled in the art to which an invention of this character appertains, when the space between the contacts 11 is bridged or the two contacts connected together, the electrical circuit will be closed and the electrical energy supplied to the heating elements. This opening and closing of the electrical circuit at the contacts 11 is controlled automatically upon changes in the 70 temperature within the incubator.

75 The means I employ for opening and closing the electrical circuit consists of a member 12 medially pivoted as at 13 between two bracket members 14 secured to the incubator wall 5' and having a contact member secured to one end, which includes an insulating block 15 having a copper plate 16 secured thereto for engagement with the contacts 11, and an adjustable counterbalance weight 17 carried by its other end. Secured to the member 12 adjacent its pivot 13 is a disk plate 18 having adjustably secured therein a threaded screw 19 which has its longitudinal axis to one side of the pivot 13 between said 80 pivot and the contact closing member.

85 The adjusting screw 19 is connected with a thermostatic device by means of a rod 20 having its ends tapered and its upper end disposed in a tapered opening in the lower end of the adjustable screw, and its other 90 end engaged in a tapered opening in a boss

21 secured to the upper plate of a double dia-
phragm 22 forming a thermostatic expansion
chamber 23. The rod 20 passes into the in-
cubator through a tube 24 having its upper
5 end secured to the brackets 14.

The double diaphragm has its under disk
secured to one arm 25 of a U shaped bracket
member 26 having its other arm 27 remov-
ably secured to the tube 24 as at 28. The
10 thermostatic expansion chamber 23 is prefer-
ably filled with ether to make the same espe-
cially sensitive to temperature changes, and
when the heat within the incubator rises
above a predetermined degree the expansion
15 of the ether within the chamber 23 will
cause the diaphragm disk to expand and,
through the rod 20, move the member 20 on
its pivot and raise the plate 16 from engage-
ment with the contacts 11. When the tem-
20 perature within the incubator falls below a
predetermined degree, the ether within the
chamber 23 will contract and permit the
member 12 to move on its pivot and the plate
16 to rest upon the contacts 11 and complete
25 the electrical circuit.

The temperature at which the electrical
circuit will be opened or closed is controlled
by means of the adjustable screw 19 as will
be obvious. The counter balanced weight 17
30 is employed to permit the balancing of the
member 12 so that the end of the member
carrying the circuit closing plate 16 will fall
when the double diaphragm is contracted.

What I claim as my invention is:

35 1. A heating unit comprising a heating
element, an electrical circuit connected with
the heating element and having a break
therein, and means for automatically open-
ing and closing the break in said circuit in-
40 cluding a pivoted lever, a circuit closing
plate carried thereby and movable to close
the break in said circuit, and a thermostatic
expansion chamber adjustably connected
with the lever to impart a movement there-
45 to upon the temperature changes.

2. A heating unit comprising a heating
element, an electrical circuit connected with
the heating element and having a break
therein, and means for automatically open-
50 ing and closing the break in said circuit in-
cluding a counter-balanced pivoted lever, a
circuit closing plate carried thereby and
movable to close the break in said circuit,
and a thermostatic expansion chamber ad-
55 justably connected with the lever to impart

a movement thereto upon the temperature
changes.

3. An incubator including means for
maintaining the same at a constant tem-
perature comprising a heating element, an 60
electrical circuit connected therewith and
having a break therein terminating in two
contact points, a medially pivoted member,
an insulated block carried by one end of
said member, a conductor plate carried by 65
said insulating block and adapted to engage
said contact points and close the electrical
circuit, an adjustable counter-balance carried
by the other end of said member, an adjust-
ing screw carried by said member between 70
its pivot and said insulating block, bracket
members between which said pivoted mem-
ber is secured, a U shaped bracket carried by
said other bracket member, a double dia-
phragm forming a thermostatic expansion 75
chamber secured to one arm of said U
shaped bracket member, and means connect-
ing said double diaphragm with said adjust-
able screw whereby the contraction or ex-
pansion of said thermostatic expansion 80
chamber due to changes in temperature will
be imparted to said pivoted member to open
and close the circuit.

4. A device of the class described, com-
prising a medially pivoted lever, a counter- 85
balance weight carried by one end of said
lever, a circuit closure carried by the other
end of said lever, a thermostatic expansion
member, and means adjustably connecting
said member with the lever and including 90
an adjustable screw carried by said lever
and a rod having one end engageable with
the adjustable screw and its other end en-
gageable with said expansion member.

5. A device of the class described, com- 95
prising a medially pivoted lever, a counter-
balance weight carried by one end of said
lever, a circuit closure carried by the other
end of said lever, a plate carried by said
lever to one side of its pivot and having a 100
threaded opening therein, a screw bolt hav-
ing its shank adjustably mounted in said
opening and having a notched recess in its
lower end, an expansion member, and a rod
having one end engaged with said expansion 105
member and its other end engaged in the
recess of said bolt to impart the movements
of said expansion member to said lever.

In testimony whereof I affix my signature.
WILLIAM G. NELSON.
